BY

M. H. Langbridge, ATTORNEY.

UNITED STATES PATENT OFFICE.

HARRY W. DYER, OF NEW YORK, N. Y.

REVOLVING DOOR.

Application filed January 14, 1924. Serial No. 685,950.

To all whom it may concern:

Be it known that I, HARRY W. DYER, a citizen of the United States, and resident of New York city, in the county of New York and State of New York, have invented certain new and useful Improvements in Revolving Doors, of which the following is a specification.

This invention relates to revolving doors and particularly to doors of this class in which the wings may be folded together so as to obtain a wide exit from public buildings. Doors of this type usually have a vertical central shaft supporting the wings which revolve in a cylindrical opening. These wings are arranged to fold together and are held in fixed and spaced relation by connections between the wings. This invention is directly concerned with the means for holding these wings which may be released between any pair of wings for folding purposes; also, which will automatically release when undue pressure is applied against the wings or against the holding means itself such as might arise in case of panic. This invention is applied to the outside of the wings without any preparation, is simple, rugged and comparatively inexpensive.

The novel features of this invention will be better understood from the following specification and the accompanying drawings, in which, Fig. 1, is a plan view of a four wing revolving door with my invention in place, Fig. 2 is a detail of an alternative construction on the wings of the doors, Fig. 3, is a plan view of the door in the folded position, Figs. 4 and 5, show the construction of the holding mechanism and its operation, Fig. 6 is a sectional view on line 6—6 of Fig. 5; Fig. 7 is a plan view and Fig. 8 is an elevation of the slide bar used with this invention and Fig. 9 shows in detail a method of attaching the ends of the flexible connection.

Revolving doors, according to standard practice, have a number of wings, usually from four to eight, revolving with an axial supporting shaft in a cylindrical chamber. These wings are pivotally mounted upon a plurality of discs which are carried by the supporting shaft so that the entire door may be collapsed by folding the wings upon their pivots against each other and thereby leave an open passage through the doorway. In the normal position the wings must be held

in spaced relation and rigid relative to each other as they revolve. For this purpose a flexible connection is tightly drawn between the wings and when released permits the wings to fold upon each other.

A connection for this purpose heretofore used consists of a chain or cable secured by a universal joint to one wing of the door and by a spring latch to the opposite wing. This connection may be unlatched and released between any pair of wings so that all of the wings may be folded together. This construction, however leaves the unlatched end of the connection loose and the attaching mechanism for these connections must be built into the wings of the door.

In the present invention I provide a flexible connection between the wings of the door which, with the wings form a triangle with the base or diagonal of the triangle opposite the centre shaft and the legs parallel with the adjacent wings. The ends of this connection are rigidly secured to the wings and it is tightened or slackened by a holding device which slides on a bar secured to the wing and which varies the length of the legs relative to the base of the triangle. Preferably a holding device is provided on each of the opposing wings so that each leg of the triangle may be varied to the same extent. The wings can thus be released for folding by moving the holding devices towards the centre of the door and, conversely, are tightened by moving the holding devices away from the centre.

In a case of emergency it is desirable that the door collapse when undue pressure is applied to the wings. I provide for this condition in the present invention in two ways, first: The holding devices are latched in the position which tightens the connection and this latch will automatically release when an excessive strain is applied to it and, second; when the base of the triangular connection is deflected such as would occur by a person leaning against it, the holding device is automatically unlatched permitting the door to collapse.

The corners of the triangle adjacent the base are secured by passing over a pulley on an arm which is pivoted to the holding device. This arm, being free to move, assumes a position in line with the resultant of the forces acting upon the base and leg of the triangle and moves as this resultant

is changed. A lever is associated with this arm and arranged to release the latching mechanism when moved in a predetermined direction. This direction corresponds to the 5 direction of the resultant when the base of the triangle is deflected towards the centre of the door so that deflecting the base will unlatch the holding devices and permit the wings to fold. In this connection it is 10 here pointed out that since the legs of the triangle are parallel with the wings, any movement tending to make the angles adjacent the base more acute will change the resultant to release the holding device. If, 15 therefore the angle between any pair of wings is increased beyond the normal position the holding devices will be released, and if one holding device is unlatched and the angle of the wings increased the other 20 holding device will be automatically unlatched due to the change in the resultant forces arising from the acute angle at the base of the triangle.

Referring to the drawings, 11 represents 25 the vertical shaft upon which the door revolves, 12 represents a disc rigidly supported by shaft 11 upon which the wings 13, 14, 15 and 16 are pivotally secured; these discs are usually provided in pairs, one at the top 30 and one at the bottom of shaft 11. The normal position of the wings is shown in Fig. 1, which, in a four wing door are placed at right angles to each other and are held rigid in this relation by the flexible connections 22 35 extending between opposite wings as shown.

A slide bar 31, hereafter more fully described, is secured to each wing as shown and retains the holding device 51 which engages the connection 22 as it turns to form 40 the legs of the triangle 21 of which 22 is the base. It is apparent that if the holding devices 51 are moved towards the centre shaft 11 the legs 21 will be shortened and the base of the connection 22 will be correspondingly increased. When the base between any pair of wings is increased in 45 length, these wings may be turned in opposite directions to collapse the door as indicated in Fig. 3. The door may be restored to the normal position by opening out the wings and moving out the holding devices 51 to tighten the connection 22.

As shown in Fig. 1, the ends of the flexible connection 21 are secured to the slide bars 55 31 so that each triangle is an individual unit in itself. However, the flexible connection may be continuous between each pair of triangles by using the alternative construction shown in Fig. 2. In this case the legs 60 21 are looped around the pulley 25 which passes through the wing 16 and is mounted upon the plunger 26 which engages the coil spring 27 and thereby provides an initial tension for the connections 21.

65 The slide bar is constructed as shown in

Figs. 7 and 8. The bar 31 is provided with side grooves 36 and 37, Fig. 6, and with stops 32 and 33 at each end. This bar 31 is secured to the wing by screws through the openings 34 so that it can be quickly 70 attached or removed without injuring the door. A sliding member 39 with a limited movement is provided at the inner end to support the hook 40 which is adjustably 75 secured to the member 39 by screw 41 as indicated in Fig. 9. An extension 42 from 39 moves in slot 38 and engages spring 43. This applies an initial tension to hook 40 and to the legs 21 which are secured to this 80 hook by the compression of spring 43 at the same time the spring is concealed and does not form an obstruction on the wing of the door.

The holding device comprises a sliding member 51 having jaws 52 and 53 which 85 engage the grooves 36 and 37 as indicated in Fig. 6. Pivoted at 54 to this member is the latch bar 55 which is engaged by the flat spring 56 to hold the tooth 58 in engagement with one of the notches 35 in bar 31. These 90 notches are required only at the end of the bar as shown, the remainder of the bar is plain so that this member will slide freely along it. The latch bar 55 is provided with an extension 57 as shown which may be used to unlatch 51 by the pressure of the fingers. The tooth 58 has its edges inclined so that if the pressure on its becomes excessive it 95 will be released from the inclined notch against the action of spring 56 and thereby 100 unlatch 51.

The arm 62 supporting pulley 61 is pivoted to 51 at 63. The flexible connections 21 and 22 in the normal position pass over the pulley as shown in Fig. 4 and the resultant 105 forces on these connections position arm 62 as hereafter described on the line indicated by *a*. Moving cooperatively with 62 is the lever arm 64 pivoted at 63 having a slot 66 at its outer end. This slot engages a pin 65 projecting from the latch bar 55 so that when the lever 64 is moved to the right the latch is released and the sliding member 51 is free to move on the slide bar.

The latch is shown released in Fig. 5 due 110 to a change of the resultant acting upon arm 62. The base 22 has been deflected from the normal position indicated by *c* to the position *d*; this changed the resultant from the normal position *a* to the position *b* and this moves arm 64 to the right releasing the latch as shown. In Fig. 4 it will be noted that the operation of the latch is not affected when the resultant is normal and the slot 66 permits a free movement of the latch bar in this position. The position of leg 21, Fig. 1 is substantially constant and parallel to the wings and anything tending to make the angle between 21 and 22 more acute than the normal angle will move lever 115 120 125 130

64 to the right and unlatch the holding device.

The lever 64 is preferably longer than arm 62 so that a movement sufficient for releasing the latch will be obtained by a comparatively small change in resultant. The position of lever 64 relative to arm 62 depends upon the construction and upon the angle between the wings. This relation 10 may be adjusted by the screw 71 as indicated in Fig. 5, the arm 64 being pivoted at 63 and angularly adjusted relative to arm 62 but in Fig. 4, 62 and 64 move integral with each other on pivot 63.

15 I have illustrated one embodiment of my invention but it is apparent that the principles herein disclosed admit of a variety of applications which are fully contemplated by my invention.

20 Having thus described my invention, I claim:

1. A revolving door of the class described having wings arranged radially about an axial supporting member and an extensible 25 flexible connection extending between adjacent wings and holding said wings in spaced relation and adjustably positioned means on said wings for securing said connection to said wings.

30 2. A revolving door of the class described having wings arranged radially about an axial supporting member, a flexible connection extending between adjacent wings and holding said wings in spaced relation and fasteners slidably adjustable on said wings for securing said connection to said wings.

35 3. A revolving door of the class described having wings arranged radially about an axial supporting member and a flexible connection 40 between adjacent wings holding them in spaced relation, said connection looped back in the plane of said wings and means adjustably positioned on said wings around which said loops are formed.

45 4. A revolving door of the class described having movable wings, an extensible flexible connection holding said wings in spaced relation, said connection having its ends secured to adjacent wings, means for tightening 50 both ends of said connection including latching devices and means for releasing said latching devices.

55 5. A revolving door of the class described having wings arranged radially about an axial supporting member and a flexible connection between adjacent wings holding them in spaced relation, said connection looped back in the plane of said wings, a device 60 adjustably positioned on said wings around which said loops are formed, a latch for securing said device and means whereby said latch is released by pressure on said connection towards said supporting member.

65 6. A revolving door of the class described having wings arranged radially about an

axial supporting member and a flexible connection between adjacent wings holding them in spaced relation, said connection looped back in the plane of said wings, means for securing said connection to said 70 wings and means whereby the position of said securing means is changed so as to lengthen said connection when said wings are spread beyond their normal position.

7. A revolving door of the class described 75 having movable wings, a flexible connection holding said wings in spaced relation, a pivoted arm secured to each of said wings, said connection engaging said arm in two directions so that the arm assumes a position 80 according to the resultant of the forces on said connections and means for releasing said arm when the resultant is changed.

8. A revolving door of the class described 85 having movable wings, a flexible connection holding said wings in spaced relation, a pivoted arm secured to each of said wings, said connection engaging said arm in two directions so that the arm assumes a position 90 according to the resultant of the forces on said connections and means for releasing the tension on said connections when the resultant is deflected towards a wing of the door.

9. A revolving door of the class described 95 having wings arranged radially about an axial supporting member and a flexible connection between adjacent wings holding them in spaced relation, the ends of said connection looped back in the plane of said wings, tightening means, including a pivoted arm, adjustably secured to said wings and around which said loops are formed, the resultant forces in said connection moving said arm to a normal position and means whereby, when said arm moves from said normal position, said tightening means is released. 100

10. A revolving door of the class described 105 having movable wings, a flexible connection holding said wings in spaced relation, a slide bar on each of said wings, a holding member sliding on each of said bars and means whereby said holding members may be positioned to tighten or slacken said connection.

11. A revolving door of the class described 115 having movable wings, a flexible connection in tension holding said wings in fixed relation and having its ends secured to said wings, a slide bar on said wing, a holding member sliding on said bar and means whereby said connection is tightened by positioning said holding member on said bar. 120

12. A revolving door of the class described 125 having movable wings, a flexible connection in tension holding said wings in fixed relation, slide bars on each of said wings, members slidable on said bars for tightening said flexible connection, a latch for said members and means for manually releasing said latches. 130

13. A revolving door of the class described having movable wings, a flexible connection holding said wings in fixed relation, slide bars on each of said wings, a sliding member on said bars for tightening each of said connections, a latch for each sliding member and means operated by said connection for releasing said latch.
14. A revolving door of the class described having movable wings, a flexible connection holding said wings in spaced relation, slide bars on each of said wings having teeth, a sliding member on each of said bars having a latch engaging said teeth, said sliding member arranged to regulate the tension on said connection.
15. A revolving door of the class described having movable wings, a flexible connection holding said wings in spaced relation, slide bars on each of said wings, a sliding member on each of said bars having a latch, said sliding member arranged to regulate the tension on said flexible connection and a lever for releasing said latch.
16. A revolving door of the class described having movable wings, a flexible connection holding said wings in spaced relation, slide bars on each of said wings, a sliding member on each of said bars, having a latch, said sliding member arranged to regulate the tension on said flexible connection and a lever operated by said connection for releasing said latch.
17. A revolving door of the class described having movable wings, a flexible connection holding said wings in spaced relation, slide bars on each of said wings, a sliding member on each of said bars having a latch and a pivoted arm with a pulley, said connection passing over said pulley and an extension on said arm arranged to release said latch.
18. A revolving door of the class described having movable wings, a flexible connection holding said wings in spaced relation, slide bars on each of said wings, a sliding member on each of said bars having a latch and a pivoted arm with a pulley, said connection passing over said pulley and arranged to release said latch when the resultant forces acting on said pulley are in a predetermined direction.
19. A revolving door of the class described having movable wings, a flexible connection holding said wings in fixed relation, slide bars on each of said wings, a sliding member on each of said bars having a holding latch and arranged to regulate the tension on said connections and a plurality of independent means for releasing said latch.
20. A revolving door of the class described having radially arranged movable wings, an extensible flexible connection holding said wings in spaced relation, the ends of said connection looped back in the plane of said wings, a compression spring and the ends of said connection held taut by said compression spring.
21. A revolving door of the class described having wings arranged radially about a vertical supporting member, a flexible connection holding said wings in spaced relation, the ends of said connection looped back in the plane of said wings, a sliding member and a spring on each of said wings, said sliding member associated with said spring and arranged to hold the ends of said connection taut.

Signed at New York in the county of New York and State of New York, this 14th day of September, A. D. 1923.

HARRY W. DYER.
